(57) **CLAIM**
The ornamental design for a bottle, as shown.

DESCRIPTION

FIG. 1 is a perspective view of the back side of the bottle;
FIG. 2 is a right perspective view of the front side of the bottle;
FIG. 3 is a front view of the bottle;
FIG. 4 is a back view of the bottle;
FIG. 5 is a right side view of the bottle;
FIG. 6 is a left side view of the bottle;
FIG. 7 is a top view of the bottle; and,
FIG. 8 is a bottom view of the bottle.

The broken lines in FIG. 8 are included for the purpose of illustrating a portion of the bottom that forms no part of the claimed design.

1 Claim, 5 Drawing Sheets
